US00D753174S

(12) **United States Design Patent**
Cojuangco et al.

(10) **Patent No.:** **US D753,174 S**
(45) **Date of Patent:** **** Apr. 5, 2016**

(54) **DISPLAY SCREEN PORTION HAVING A GRAPHICAL USER INTERFACE FOR PATIENT MONITORING**

(71) Applicant: **Proteus Digital Health, Inc.**, Redwood City, CA (US)

(72) Inventors: **Danielle Schulze Cojuangco**, San Francisco, CA (US); **Todd Nathan Rinker**, Portland, OR (US); **Arna Diana Ionescu**, San Francisco, CA (US)

(73) Assignee: **Proteus Digital Health, Inc.**, Redwood City, CA (US)

(**) Term: **14 Years**

(21) Appl. No.: **29/500,728**

(22) Filed: **Aug. 27, 2014**

CLAIM

The ornamental design for display screen portion having a graphical user interface for patient monitoring, as shown and described.

DESCRIPTION

FIG. 1 is a front view of a display screen portion having a graphical user interface for patient monitoring, showing our new design in the environment of a mobile device; and, FIG. 2 is a front view of a display screen portion having a graphical user interface for patient monitoring, showing our new design.

No claim is made to the dashed lines, dashed image, or text. Said dashed lines, dashed image, and text being presented only for the environmental purposes.

1 Claim, 2 Drawing Sheets
